UNITED STATES PATENT OFFICE

HEINRICH HEETKAMP, OF DUISBURG, GERMANY, ASSIGNOR TO DEMAG AKTIENGESELLSCHAFT, OF DUISBURG, GERMANY

TUBE DRAWING BENCH

Application filed April 25, 1930, Serial No. 447,300, and in Germany February 20, 1930.

It has been customary to control tube drawing benches from a platform, the supervisor watching the position of the working mandrel in the draw ring bed or following the movement of the end of the mandrel shaft, and this requires special attention.

It is proposed according to the invention to provide a special distance indicator advantageously so arranged that, seen from the control platform, it lies in the direction of the draw ring bed. With the distance indicator in this position it can be seen by the supervisor who at the same time watches the movements in the draw ring bed. This considerably facilitates supervision. The distance indicator is advantageously formed of a vertically disposed scale along which moves a pointer which is for example fitted with a moving nut.

20 The invention is diagrammatically illustrated by way of example in the accompanying drawing.

Figure 1 is a plan of the bench, and

Figure 2 is a corresponding end elevation.

25 The part of the bench which guides the operating rack 9 and the shaft 10 of the mandrel is denoted by 1 and the adjoining draw ring bed by 2. The rack 9 is driven from the gearing 7 by means of a pinion 12 and the 30 mandrel shaft 10 is guided in a tubular guide 13 carried in a series of spaced bearing members 14. The control platform is indicated in Figure 2 by full lines and in Figure 1 by dot and dash lines and is denoted by 3. The distance indicator 4 is provided beside the draw ring bed, the screw-threaded spindle 11 which is employed being driven by the shaft 5 disposed beside the bed 1. The pointer is denoted by 6 and is carried by a nut on the 35 spindle 11, which nut is constrained against rotation. The shaft 5 is driven by the gearing 7 through the bevelled wheels 8. The particular construction of the distance indicator is of no importance to the invention. It is also possible to provide movable marks on the scale 4 to show the supervisor clearly particular positions of the mandrel during the working of the bench. It is also advantage- 40 ous to provide the pointer 6 with a light in

order to make it easier to follow the movements of the mandrel.

I claim:

1. A tube draw bench provided with a plurality of draw rings, a mandrel, means for propelling the mandrel through the draw rings, an elongated tubular guide through which said mandrel is guided, a mandrel position indicator disposed adjacent the draw bench, an index movable in relation to said indicator, and a mechanism driven from the mandrel moving mechanism for operating the said index relatively to the indicator. 55

2. A tube draw bench provided with a plurality of draw rings, a mandrel, means for propelling the mandrel through the draw rings, an elongated tubular guide through which said mandrel is guided, a control platform adjacent the draw bench, a mandrel position indicator disposed adjacent the draw 60 bench bed when viewed from the control platform, a movable index upon said indicator, a rotatable shaft lying adjacent the draw bench, a rotatable spindle for operating the said index, bevel gears driven from the said 65 shaft for rotating the said spindle, and bevel gears connecting the said shaft with the mechanism for moving the mandrel. 70
